TRIPLE DUAL COMPARATIVE FALLING
BALL VISCOMETERNoel L. McHone, Redwood City, Calif., assignor to
Chevron Research Company, San Francisco, Calif.

Filed Dec. 1, 1972, Ser. No. 311,082

Term of patent 14 years

Int. Cl. D10—05

U.S. Cl. D10—84

The figure is a perspective view of the triple dual comparative falling ball viscometer showing my new design.

The spherical bodies shown in the viscometer are not stationary and their position in the figure is merely representative.

I claim:

The ornamental design for a triple dual comparative falling ball viscometer, substantially as shown and described.
